SHOE SEWING MACHINE

Erastus E. Winkley, Lynn, Mass., assignor to
 United Shoe Machinery Corporation, Paterson,
 N. J., a corporation of New Jersey

Application February 18, 1936, Serial No. 64,495

13 Claims. (Cl. 112—34)

The present invention relates to shoe sewing machines and, more particularly, to machines of the so-called McKay type, the stitch-forming devices of which comprise a straight hook needle and the work support of which consists of a rotatable work entering horn having an angularly disposed upper portion constructed with a work engaging tip, a needle receiving opening and needle threading or other thread manipulating devices within the opening.

To permit sewing small pointed shoes in a machine of this type, the tip of the horn is made as small as possible. The needle receiving opening is usually made concentric with the rotary axis of the horn at the center of the work engaging surface of the horn tip. Some machines heretofore constructed have been provided with thread fingers or other measuring devices for drawing an extra length of thread during formation of a stitch through the needle threading devices so that the thread between a previous stitch and the point of engagement with the needle in threading it will be sufficient to permit the needle to be withdrawn entirely from the work before the said thread length is pulled tight. In previous machines having a thread measuring finger, it has been necessary to increase the dimensions of the tip of the horn because the thread finger can act only at this location between the needle threading devices and the tip. This requires such an increase in dimensions at the horn tip as to cause difficulty in sewing small shoes or to render it inconvenient to guide a shoe properly in the machine without producing irregularities in the seam. Also, with a horn tip of such increased dimensions, it is impossible to guide the seam close to the edges of a shoe sole because the relatively greater distance between the needle receiving opening and the outer edges of the horn tip serves to gage the seam at a corresponding distance from the inner surfaces of the upstanding upper being sewed.

The objects of the present invention are to provide a novel and improved sewing machine of the McKay type by which a more satisfactory seam may be sewed and in which the shoe may be manipulated and controlled more easily than heretofore. A more particular object of the invention is to provide, in a machine of this type, a shoe supporting horn having devices for measuring thread between the last formed stitch in the work and the needle threading devices without so enlarging the dimensions of the horn tip as to render it difficult to form a seam close to

the edge of a shoe sole. It is, accordingly, a feature of the invention to provide within the horn of a sewing machine of the McKay type a novel thread measuring device constructed and arranged to withdraw a supply of thread by winding it in a curved path within the confines of the horn tip so as to reduce the space requirements for the measuring device in the tip as much as possible. In the illustrated embodiment of this feature of the invention, the thread guiding portion of the thread measuring device is formed with a convex surface surrounding the rotary axis of the horn.

To permit a seam to be formed close to an upstanding portion of a work piece, such as the inner surface of a shoe upper, when sewing the sole, the opening for receiving the needle of the machine embodying the present invention is disposed at one side of the rotary axis of the horn close to one edge of the horn tip rather than being concentric to the horn axis, and means is provided for maintaining the needle opening in alignment with the needle at all times, regardless of the angular position of the horn. As an additional precaution against improperly guiding the work, a further feature of the invention consists in providing a plate at the tip of the horn having a work supporting flange arranged at one side of the horn tip to extend always in the line of feed from the needle opening, so that the presser foot and work feeding devices of the machine will cooperate with the supporting flange to guide and feed the work more effectively.

These and other features of the invention will be readily understood by one skilled in the art from the following description, taken in connection with the accompanying drawings, in which Figure 1 is a view in side elevation of a McKay sewing machine illustrating one embodiment of the present invention; Figure 2 is a sectional view, on a larger scale, of a portion of the actuating mechanisms of the machine; Figure 3 is a detail view, partly in section, taken along the line 3—3 of Figure 1, showing the needle engaging the work; Figure 4 is a plan view, on an enlarged scale, of the work supporting tip portion of the horn in the machine; Figure 5 is a similar view of the horn tip with a work supporting plate removed; Figure 6 is a partial sectional view, taken along the line 6—6 of Figure 4; Figure 7 is a partial sectional view, taken along the line 7—7 of Figure 4; Figures 8, 9 and 10 are plan views of the parts shown in Figure 5, illustrating successive positions assumed during measure-

ment of thread between the work and the needle looping devices; Figures 11, 12 and 13 are sectional views similar to that shown in Figure 7, illustrating respectively the positions of the parts shown in Figures 8, 9 and 10; and Figure 14 is a detail view in perspective of a block in the tip portion of the horn.

The invention is herein disclosed as applied to a McKay shoe sewing machine of the chain-stitch type, such as illustrated and described in U. S. Letters Patent No. 710,612, granted October 7, 1902 to E. P. Richardson; No. 1,177,581, granted March 28, 1916 to W. C. Meyer; and No. 1,887,638, granted November 15, 1932 to G. T. Hart, Jr., to which patents reference may be had for a full and complete description of the construction and operation of the machine, and of such parts as are not particularly referred to in the present application. While the illustrated machine in which the invention is embodied is constructed to form a chain-stitch seam, the features of the invention are capable of more general application to lockstitch and other types of sewing machines.

With reference to the drawings, the outer portion of the machine, including the straight hook needle 2, a cast-off 4, a feed point 6 and a presser foot 8, together with their operating mechanisms, are substantially the same as in the machine described in the Richardson patent above referred to. The needle operates in the usual way towards and from the tip end of a rotatable work entering horn 10, within which are disposed means for engaging the thread with the needle during each reciprocation thereof.

The means for engaging the thread with the needle comprises a block 12 at the tip of the horn having a needle receiving perforation or opening 14 into which the needle enters at the lower part of its stroke. After the needle has entered the perforation 14, the needle is rotated and the thread is engaged in the barb of the needle, as shown in Figure 13. The mechanism for rotating the needle includes a cam actuated rack 13 engaging gear teeth on the needle carrying bar. During the upward movement of the needle, the thread is drawn from the tip of the horn in the form of a loop through the work supported on the horn, and is acted upon by a loop spreader 15. During the succeeding downward stroke of the needle, the needle is returned to its original angular position, substantially as described in the Hart patent, above identified.

In the machines of the patents noted above, the needle, when in its lowest position, engages the thread in the horn tip at a point where there is no extra thread between the previously formed stitch and the needle. As a result, when the threaded needle withdraws from the work, the thread is caused to slide through the needle barb under a heavy frictional grip between the sides of the needle perforation in the work.

In order to provide a surplus of thread between the last formed stitch in the work and the needle as it passes through the work, so that no movement of the thread in the needle barb will occur until the needle has fully withdrawn from the work, the novel thread measuring device is provided within the tip of the horn. Within the upper surface of the block 12 is formed a small recess 16 in which is disposed a rotary circular disk member 18. The disk member is secured to the upper end of a vertical shaft 20 rotatably mounted in the block 12, and so arranged as to be concentric with the axis about which the horn

rotates. Extending from the disk member 18 is an arm 22 arranged, when the member 18 is rotated, to engage the thread extending between the needle receiving perforation 14 and the work. The disk member is rotated sufficiently to cause the thread to be drawn aside from its normal path, and an extra supply to be measured between the work and the needle perforation 14. After a sufficient amount of thread has been drawn aside, the thread is disengaged from the arm 22 and rendered available. When the needle is threaded, its upward stroke draws one side of the loop formed thereon from the main supply, and the other side of the loop from the extra supply thus rendered available between the last formed stitch and the needle.

As a protection for the thread measuring disk member, the recess 16 at the top of the block 12 is covered by a work supporting plate 24 having a needle opening 26 directly above and in alignment with the perforation 14 in the block 12. The plate 24 and the block 12 within the recess 16 are formed with curved thread guiding flange portions 28 about the convex surfaces of which the thread is wound by the continued measuring movement of arm 22. The thread engaging surfaces of the flanges 28 are provided with a helical curvature and with an increasing radius about the axis of the horn in the direction of the thread measuring movement of the arm 22. When, during the measuring movement of the arm, the radius of the thread engaging surfaces becomes greater than the distance between the end of the arm and its rotary axis, the thread will be disengaged from the arm.

In order to permit the seam to be sewed close to the inner upstanding surface of a shoe upper even though the tip of the horn is somewhat larger than in the usual machine, and to provide a compact and conveniently assembled construction, the needle receiving perforation 14 in the block 12 is made eccentric to the rotary axis of the horn, and closer to one edge of the horn tip. The needle, accordingly, is mounted in the machine at a position at one side of the rotary horn axis, so that it may enter the needle receiving perforation when the block 12 is in the proper position. To maintain the needle receiving perforation in alignment with the needle, the block 12 is rotatably mounted at the tip of the horn, and mechanism is provided for preventing rotation of the block with the horn. The block is surrounded within the horn by a circular ring 30 engaged by radial pins 32 passing through the side walls of the horn at the tip. The ring 30 fits within a recess around the upper edge of the block 12 and the work supporting plate 24 which is secured to the block by means of screws 34, holds the block from displacement.

The mechanism for preventing rotation of the block as the horn is rotated comprises gear teeth formed in the under side of the block 12 engaging a gear 36 fixed to the upper end of a tubular shaft 38 rotatably mounted in the upper portion of the horn. To the lower end of the shaft 38 is secured a bevelled gear 40 engaging a similar gear 41 secured to the upper end of a tubular shaft 42, the lower end of which carries a bevel gear 43. The gear 43 meshes with a gear 44 at the upper end of a tubular member 45 having a flanged lower end made fast to the machine frame by a screw 46. The tubular member 45 extends downwardly through the hollow shaft portion 47 of the rotary horn supporting spindle, and between the flanged portion of the tubular member 75

45 and the end of the hollow shaft portion 47 is mounted a horn supporting bearing 48.

The driving connections for the thread measuring disk member 18 comprise a bevel gear 52 at the lower end of the shaft 20 to which the disk is secured, a bevel gear 54 meshing with gear 52, an inclined hollow shaft 56 rotatable within the tubular shaft 38, on the upper end of which inclined shaft the gear 54 is secured, a bevel gear 58 at the lower end of shaft 56 engaging a similar gear 60 at the upper end of a drilled shaft 61 within the shaft 42, the lower end of which drilled shaft carries a beveled gear 62 meshing with a gear 63 at the upper end of a drilled shaft 64. At the lower end of shaft 64 is a spur gear 65. A rack 66 meshes with gear 65 and is supported by a horizontal reciprocating rod 68 operated by a cam follower 70 at its rearward end. The cam follower 70 engages a cam 72 at the lower end of a vertical rotating shaft 74 driven by gears 76 from the main sewing shaft of the machine in proper timed relation to the reciprocations of the needle.

The sewing thread is led to the tip of the horn 25 through the shafts 64, 61 and 56, a central passage 78 in the shaft 20, a segmental radial opening 80 in the same shaft, a similar registering opening 82 in block 12, the perforation 14 and opening 26 in the work supporting plate 24. The 30 segmental openings 80 and 82 extend through relatively large angles about the shaft 20 to prevent cutting or binding the thread in any positions of the parts.

In the machines of the patents above referred 35 to, the presser foot and the feed point are not directly above the work supporting surface of the horn tip. To insure that the work in the present machine will be adequately supported beneath the presser foot and feed point, the plate 24 is provided with flanged portions 84 and 86, one of which extends in the line of feed in advance of the needle opening in the plate 24, and the other of which extends in the opposite direction with a continuous interconnecting edge 40 past which the work may easily be guided.

The nature and scope of the invention having thus been indicated, and the construction embodying the invention having been specifically described, what is claimed is:—

50 1. A shoe sewing machine of the McKay type having, in combination, stitch forming and work supporting devices including a straight hook needle and a rotary work entering horn having a needle receiving opening at its tip, and a thread engaging member within the tip of the horn having a thread guiding portion about which a length of thread is wound in a curved path to provide a surplus between the work and the needle as the threaded hook of the needle is drawn through the work.

60 2. A shoe sewing machine of the McKay type having, in combination, stitch forming and work supporting devices including a straight hook needle and a rotary work entering horn having a needle receiving opening at its tip and a thread engaging member within the tip of the horn having a thread guiding portion about which a length of thread is wound to provide a surplus between the work and the needle as the threaded hook of the needle is drawn through the work, said thread guiding portion being formed with a convex thread engaging surface surrounding the rotary axis of the horn.

70 3. A shoe sewing machine of the McKay type having, in combination, stitch forming and work

supporting devices including a straight hook needle and a rotary work entering horn having a needle receiving opening at its tip, a member having a thread guiding portion within the tip of the horn, and means for winding the thread about said portion to provide a surplus between the work and the needle as the threaded hook of the needle is drawn through the work.

4. A shoe sewing machine of the McKay type having, in combination, stitch forming and work supporting devices including a straight hook needle and a rotary work entering horn having a needle receiving opening at its tip, a member having a thread guiding portion within the tip of the horn, the guiding portion being formed with a convex surface surrounding the rotary axis of the horn, and means for winding a loop of thread about said surface through a sufficient angle to provide, when released, a surplus between the work and the needle as the threaded hook of the needle is drawn through the work.

5. A shoe sewing machine of the McKay type having, in combination, stitch forming and work supporting devices including a straight hook needle and a rotary work entering horn, a block 25 in the tip of the horn having a needle receiving opening and mechanism for providing a surplus of thread between the work and the needle as the threaded hook of the needle is drawn through the work comprising a thread guiding portion of said 30 block, a shaft mounted in said block and an arm on said shaft for engaging the thread extending through the needle opening in the horn tip when the shaft is rotated to wind the thread about the guiding portion of the block.

6. A shoe sewing machine of the McKay type having, in combination, stitch forming and work supporting devices including a straight hook needle and a rotary work entering horn, a block in the tip of the horn having a needle receiving 40 opening and mechanism for providing a surplus of thread between the work and the needle as the threaded hook of the needle is drawn through the work comprising a shaft rotatable in the block, a convex helical surface on said block 45 surrounding said shaft, and an arm on said shaft for engaging the thread extending through the needle opening in the block when the shaft is rotated to wind thread about said convex surface and to release the thread at a point where said 50 surface extends beyond the end of the arm.

7. A shoe sewing machine of the McKay type having, in combination, stitch forming and work supporting devices including a straight hook needle and a rotary work entering horn, a block 55 mounted within the horn tip for rotation about the rotary axis of the horn, needle threading means comprising a needle receiving opening in said block eccentric to the rotary axis of the horn, means for maintaining the needle opening 60 in alignment with the needle when the horn is rotated, mechanism for rotating the needle when the hook of the needle enters the needle receiving opening, and means for providing a surplus of thread between the work and the needle when the threaded hook of the needle is drawn through the work comprising an arm rotatable concentrically with the horn axis in the block to engage the thread extending through the needle opening and a thread guiding portion of the block about 65 70 which the thread is wound by the thread engaging arm.

8. A shoe sewing machine of the McKay type having, in combination, stitch forming and work supporting devices including a straight hook nee- 75

- dle and a rotary work entering horn, a block within the horn tip having a needle receiving opening disposed at one side of the rotary axis of the horn, and means for maintaining the block in a position with the needle opening in alignment with the needle when the horn is rotated.
9. A shoe sewing machine of the McKay type having, in combination, stitch forming and work feeding devices including a straight hook needle, 10 a feed point, a presser foot acting on the work in advance of the needle, a rotary work entering horn, a work supporting plate having a needle receiving opening rotatably mounted on the horn tip, means for maintaining the plate in fixed 15 angular position as the horn is rotated, and a work supporting flange on said plate extending in the line of feed from the needle opening beyond the side of the horn tip to hold the work in cooperative relation to the work feeding devices.
10. A shoe sewing machine of the McKay type having, in combination, stitch forming and work supporting devices including a straight hook needle and a rotary work entering horn, a block at 20 the tip of the horn having a needle receiving opening disposed at one side of the rotary axis of the horn, means for maintaining the block with the needle opening in alignment with the needle when the horn is rotated, and means for threading the needle comprising mechanism for 25 rotating the needle after it enters the needle opening.
11. A shoe sewing machine of the McKay type having, in combination, stitch forming and work supporting devices including a straight hook needle and a rotary work entering horn having a 30

needle receiving opening at its tip, and a rotary disk within the tip of the horn having a peripheral thread guiding portion about which a length of thread is wound when the disk is rotated to provide a surplus between the work and the needle as the threaded hook of the needle is drawn through the work. 5

12. A shoe sewing machine of the McKay type having, in combination, stitch forming and work supporting devices including a straight hook needle and a rotary work entering horn having a needle receiving opening at its tip, a circular rotary disk within the tip of the horn having a peripheral thread guiding portion and an arm for engaging the thread to wind it about the disk as 10 the disk is rotated, and means for disengaging the thread from the arm to provide a surplus of thread between the work and the needle as the threaded hook of the needle is drawn through the work. 15

13. A shoe sewing machine of the McKay type having, in combination, stitch forming and work feeding devices including a straight hook needle, a feed point, a presser foot acting on the work in advance of the needle, a rotary work entering 20 horn, a work supporting plate having a needle receiving opening rotatably mounted on the horn tip, means for maintaining the plate in fixed angular position as the horn is rotated, and a pair of work supporting flanges on said plate 25 disposed to extend in the line of feed at opposite sides of the horn tip and formed to present a continuous edge past which the work is guided. 30

ERASTUS E. WINKLEY. 35
